UNITED STATES PATENT OFFICE

EMIL A. SCHUELKE, OF MERIDEN, CONNECTICUT, ASSIGNOR TO THE NAPIER COMPANY,
OF MERIDEN, CONNECTICUT, A CORPORATION

COMBINED DESK BLOTTER AND BOX

Application filed September 30, 1929. Serial No. 396,053.

This invention relates to an improvement in combined desk blotters and boxes. Desk blotters of this type are commonly formed with a segmental bottom which is covered by 5 a piece of blotting-paper which is generally clamped to the base by a plate with a handle screwed through the top and into the base.

The object of this invention is to form a hollow base to provide a box for cigarettes, 10 vanity or other articles and the invention consists in the construction as hereinafter described and particularly recited in the claims.

In the accompanying drawings:

Fig. 1 is a plan view of a combined desk 15 blotter and cigarette box constructed in accordance with my invention and shown in the closed position;

Fig. 2 is a side view of the same;

Fig. 3 is an end view of the same;

20 Fig. 4 is a sectional view on the line 4—4 of Fig. 1; and

Fig. 5 is a plan view of the box with the cover open.

In carrying out my invention, I employ a 25 box 10 having a longitudinally bowed bottom 11, and the ends of this bottom are turned down over the outside of the bottom, forming lips 12 for the reception of the ends of a strip 13 of blotting-paper. The upper edge of one 30 of the side walls 14 of the box is formed with knuckles 15, and a flat top 16 is formed with corresponding knuckles 17, through which knuckles a pin 18 extends so as to hinge the cover to the box. This cover is formed at its 35 front and ends with a short flange 19 which sets over the edge of the box, and the cover is provided with a suitable knob or handle 20.

A box thus formed is adapted to receive a 40 number of cigarettes or other articles, which are convenient of access at a desk and without occupying space additional to the desk blotter, and as the box and cover are formed from metal, a very attractive fitting is provided.

I claim:

45 1. A box having a longitudinally bowed bottom provided at opposite sides with lips for the reception of ends of a strip of blotting-paper, and a cover hinged to one side of the box and provided on its top with a handle.

50 2. A box having a longitudinally bowed

bottom and provided at opposite ends with lips beneath which a strip of blotting-paper may be placed, a cover hinged to one side of said box, said cover formed at its forward edge and ends with a depending flange setting over and engaging with the edges of the box and also provided on its top with a handle.

In testimony whereof, I have signed this specification.

EMIL A. SCHUELKE.
